CLAIM

The ornamental design for an office organizer, as shown and described.

DESCRIPTION

FIG. 1 is a front, right side perspective view of an office organizer showing my new design;

FIG. 2 is a bottom, rear, left side perspective view thereof; FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another top, front perspective view of the office organizer, shown with the drawer separated; and,

FIG. 10 is an enlarged view of a portion indicated in FIG. 1. The dash lines in FIGS. 1 and 10 are for the purpose of depicting the cut line of the enlarged view and form no part of the claim.
